United States Patent

Des. 241,652
Patented Sept. 28, 1976

241,652

BANKING MACHINE TERMINAL

Edward H. McCauley, Dallas, and Lewis J. O'Kelly,
Fort Worth, Tex., assignors to Docutel Corporation,
Irving, Tex.

Filed Mar. 10, 1975, Ser. No. 557,048

Term of patent 14 years

Int. Cl. D14—02

U.S. Cl. D26—5 C

FIG. 1

FIG. 3

FIG. 2

FIG. 4

FIG. 1 is a front perspective view of a banking machine terminal showing our new design;

FIG. 2 is a front elevational thereof;

FIG. 3 is a top plan view thereof; and

FIG. 4 is a right side elevational view thereof.

The back is plain and unornamented.

We claim:

The ornamental design for a banking machine terminal, as shown and described.
